United States Patent Office.

GEORGE FEIGHTNER, OF WOOSTER, OHIO.

Letters Patent No. 64,754, dated May 14, 1867.

IMPROVED MACHINE FOR MAKING WAGON-CLIPS.

The Schedule referred to in these Letters Patent and making part of the same.

TO ALL WHOM IT MAY CONCERN:

Be it known that I, GEORGE FEIGHTNER, of Wooster, in the county of Wayne, and State of Ohio, have invented certain new and useful improvements in Fifth-Wheel Axle-Clip "Swage-Block Dies;" and I do hereby declare that the following is a full, clear, and exact description of the same, reference being had to the accompanying drawings, and the letters of reference marked thereon, as forming a part of this specification, in which—

Figure 1 is a perspective, and

Figure 2 a section.

A represents a box or block of wood of suitable dimensions, upon which is secured the iron die-box B, the construction of which, and the mode of fastening, is fully shown in fig. 1. Said box is provided with holes through its bottom, as seen in fig. 2, and indicated by letters *d d*. C is a sliding die, which is operated by means of foot-pedal D and levers *e f g h* and shaft E, all connected and worked as shown in fig. 1. *i* represents a spring for the purpose of throwing the die C back when pedal D is relieved of its weight. F is also a movable die, and is operated by die C. G represents a stationary die, and should be firmly secured in its place. It should here be observed that the movable die C and stationary die G are provided upon their upper surfaces with a concave groove, and movable die F with a square-groove, as fully shown in fig. 1. The contiguous ends of grooves in C and G should also be rounding, in order to give a curve and imparting additional strength to the clips.

The operation of my machine is as follows: Take a piece of iron about six inches in length and of the proper thickness, split up the end a sufficient distance to form the base of the clip, turn out one end on each side and work the same to proper size to form the clip, then under a white heat place the iron thus formed into the block, force the die-blocks close together, holding them tightly until completed with the hammer, forming the clips and ends thereto, ready for attaching the swage-iron to complete the wheel.

I claim as my invention—

The stationary die G and movable dies C F, in combination with the die-box B, constructed as and for the purpose set forth.

In testimony that I claim the foregoing, I herewith affix my signature in presence of two witnesses.

GEORGE FEIGHTNER.
